UNITED STATES PATENT OFFICE.

GEORGE WARD BIDWELL, OF NEW HAVEN, CONNECTICUT.

DESIGN FOR A CLOCK-CASE.

SPECIFICATION forming part of Design No. 19,270, dated August 20, 1889.

Application filed May 10, 1889. Serial No. 310,348. Term of patent 7 years.

To all whom it may concern:

Be it known that I, GEORGE WARD BIDWELL, a citizen of the United States, residing at New Haven, in the county of New Haven and State of Connecticut, have invented and produced a new and original Design for Clock-Cases, of which the following is a specification, reference being had to the accompanying drawings, forming part thereof.

10 In the accompanying drawings, Figure 1 is a front view in elevation of a clock-frame representing a screw-press provided with an elliptical banded portion or case, as shown; and Fig. 2 is an end elevation of the same.

15 A represents the clock-frame, which is a figure having the shape and several parts characteristic of a screw-press, as shown.

Between the bed and screw of the press,

and centrally held therein, is the elliptical banded portion or clock-case G, the shortest axis of the ellipse being nearly or quite parallel with the axis of the screw, as shown in Fig. 1.

The case is provided with a sash as shown in both views. 35

I claim—

The design for a clock-case herein shown and described, the same consisting in the clock-frame A, representing a screw-press having centrally held therein the elliptical banded portion or case G, as set forth.

GEORGE WARD BIDWELL.
